UNITED STATES PATENT OFFICE.

LEWIS S. DUNCAN, OF NEW YORK, N. Y.

MOISTENER.

SPECIFICATION forming part of Letters Patent No. 703,771, dated July 1, 1902.

Application filed November 12, 1901. Serial No. 81,984. (No model.)

To all whom it may concern:

Be it known that I, LEWIS S. DUNCAN, a citizen of the United States, and a resident of the city of New York, borough of Manhattan, in 5 the county and State of New York, have invented a new and Improved Moistener, of which the following is a full, clear, and exact description.

This invention relates to improvements in 10 devices for moistening the adhesive on envelop-flaps and the like; and the object is to provide a moistener of simple construction by means of which envelopes may be rapidly moistened and the moisture spread evenly 15 and thinly, thus preventing the forcing out of water and gum onto the envelop-body when the flap is pressed down.

I will describe a moistener embodying my invention and then point out the novel features in the appended claims.

Reference is to be had to the accompanying drawings, forming a part of this specification, in which similar characters of reference indicate corresponding parts in all the figures.

25 Figure 1 is a perspective view of a moistener embodying my invention. Fig. 2 is a section thereof on the line $x-x$ of Fig. 3, and Fig. 3 is a section on the line $y-y$ of Fig. 2.

The moistener comprises a water tank or 30 vessel 1, made of any suitable material and sufficiently heavy to prevent its sliding about during the operation of moistening envelopes or the like. The tank has a removable cover 2, which may be made of sheet metal, and this cover on its upper surface is inclined 35 downward in both directions lengthwise of the moistener from a central point. The object of thus inclining the cover is to permit of the quick and easy sliding of envelop-flaps 40 over the moistening-wick in either direction. At its center the cover 2 has two transverse openings 3, through which the wick material 4 passes, the said wick, of course, at its outer side passing over the bridge-piece between 45 the two openings 3.

Adjustable above the exposed or upper portion of the wick is a presser or guide plate 5. On its under side this presser or guide plate is concaved to conform substantially to the 50 formation of the exposed portion of the wick. The side portions, however, will extend

slightly below the top of the wick without touching the same, and therefore the flaps will be pressed evenly upon the wick material as the envelop is drawn through. To 55 provide for different thicknesses of paper, the plate 5 is vertically adjustable. As here shown, it has a threaded shank portion 6, extended through a slot in a plate 7, attached to one side of the cover 2, and it is held as 60 adjusted by means of a thumb-nut 8, engaging with said screw-threaded shank.

In operation it is obvious that water will be carried up in the wick by capillary attraction. The envelop-flap is to be passed over 65 the wick and underneath the plate 5. As before stated, the envelop may be entered from either side, and by placing it flat upon an inclined portion of the cover it will be guided to the wick.

Having thus described my invention, I 70 claim as new and desire to secure by Letters Patent—

1. A moistener, comprising a tank for water, a cover therefor having transverse openings, a wick looped through said openings, and a presser or guide plate vertically adjustable over the wick, substantially as specified.

2. A moistener, comprising a tank, a cover 80 therefor having its upper surface inclined downward from about its center in both directions, the said cover at its central portion being provided with openings, a wick material looped through said openings, and a 85 vertically-adjustable presser-plate concaved on its under side and arranged above the wick, substantially as specified.

3. A moistener, comprising a tank, a cover 90 therefor provided with openings, a wick looped through said openings, and a vertically-adjustable presser or guide plate above the exposed portion of the wick, the said presser or guide plate being longitudinally channeled on its under side, substantially as 95 specified.

4. A moistener, comprising a tank, a cover therefor having its upper surface inclined downward from about its center in both directions, the said cover being provided at its 100 center with transverse openings, a wick looped through said openings, a slotted plate at-

tached to one side of the cover, a presser-
plate arranged above the exposed portion of
the wick, a threaded shank on said plate ex-
tended through the slot in the plate attached
5 to the cover, and a clamping-nut on said
shank, substantially as specified.

In testimony whereof I have signed my

name to this specification in the presence of
two subscribing witnesses.

LEWIS S. DUNCAN.
